EMBOSSED PLASTIC SHEET MATERIAL OR SIMILAR ARTICLE

James M. Long, Pataskala, Ohio, assignor to Owens-Corning Fiberglas Corporation, a corporation of Delaware

Filed May 9, 1967, Ser. No. 7,025

Term of patent 14 years

(Cl. D87—3)

FIG. 1

FIG. 2

FIG. 1 is a plan view of an embossed plastic sheet material showing my new design. The design is contained within the rectangle defined by four corner markings and repeated as indicated by the extensions beyond the unit boundary.

FIG. 2 is a perspective view of the plastic sheet material shown on a reduced scale against a black background and illustrates the light reflecting character of the mono-tone sheet.

I claim:

The ornamental design for an embossed plastic sheet material or similar article, substantially as shown and described.
